UNITED STATES PATENT OFFICE

116,029

DESIGN FOR A CUFF LINK OR SIMILAR ARTICLE

George W. Headley, 3d, New York, N. Y., assignor to Paul E. Flato, New York, N. Y.

Application August 10, 1938, Serial No. 79,218

Term of patent 3½ years

To all whom it may concern:

Be it known that George W. Headley, 3d, a citizen of the United States and resident of New York city, in the county of New York and State of New York, has invented a new, original, and ornamental Design for a Cuff Link or Similar Article, of which the following is a specification, reference being had to the accompanying drawing, forming part thereof, in which,

Fig. 1 is a perspective view of a cuff link embodying my new design and showing the link in closed position;

Fig. 2 is a perspective view thereof in partly opened position; and

Fig. 3 is a plan view thereof in fully opened position.

The characteristic features of the design reside in a cuff link of the type shown having a center bar projecting outwardly beyond the opposite edges of the leaf members, together with the symmetrical aligned members projecting from the flat surfaces of the leaf members and the surface ornamentation of the flat sides of the leaves opposite to the sides having the projections.

I claim:

The ornamental design for a cuff link or similar article, substantially as shown and described.

GEORGE W. HEADLEY, III.
